REFRIGERATION

Sven W. E. Andersson, Evansville, Ind., assignor
to Servel, Inc., New York, N. Y., a corporation
of Delaware

Application October 20, 1936, Serial No. 106,507

9 Claims. (Cl. 62—5)

My invention relates to refrigeration, and more particularly to control mechanism for absorption refrigeration apparatus.

It is an object of my invention to provide an improvement in control mechanism for a refrigerator of the absorption type for regulating the minimum heat input to the refrigerator.

The invention, together with the objects and advantages thereof, will become apparent as I next describe the invention as embodied in a control mechanism like that shown in my application Serial No. 758,195, filed December 19, 1934, (Patent No. 2,123,921, granted July 19, 1938) and the features of novelty which characterize my invention will be pointed out with particularity in the claims forming a part of this specification.

In the drawings, Fig. 1 is a front elevation, partly broken away, of a refrigerator embodying my invention; Fig. 2 is a side elevation, partly broken away and in section, of the refrigerator shown in Fig. 1; Fig. 3 is an enlarged fragmentary front elevation of the control mechanism shown in connection with the refrigerator illustrated in Figs. 1 and 2; Fig. 4 is a sectional view taken at line 4—4 of Fig. 3 to illustrate parts of the control mechanism more clearly; Fig. 5 is a fragmentary sectional view taken at line 5—5 of Fig. 3; Figs. 6 and 7 are sectional views taken at lines 6—6 and 7—7, respectively, of Figs. 3 and 8; Fig. 8 is a view similar to Fig. 3 with the cover plate and internal parts of the control mechanism removed from the casing; and Fig. 9 is a sectional view taken at line 9—9 of Fig. 8 with the internal parts removed from the casing.

Referring to Figs. 1 and 2 of the drawings, I have shown my invention in connection with a refrigerator of a continuous absorption type, generally as disclosed in Patent No. 1,609,334 to B. C. von Platen and C. G. Munters, in which an auxiliary pressure equalizing gas is employed. This refrigerator comprises a cooling element or evaporator 10 disposed in a thermally insulated compartment 11 which may form a food storage space in the upper portion of a cabinet 12 and into which access may be had by a door 13. A refrigerant fluid, such as ammonia, evaporates in the evaporator 10 and diffuses into an inert pressure equalizing gas, such as hydrogen. The resulting gas mixture of refrigerant and hydrogen flows from the evaporator 10 to an absorber (not shown) in which the refrigerant is absorbed by a suitable liquid absorbent, such as water. The inert hydrogen gas is returned to the evaporator 10, and the enriched absorption liquid is conducted to a generator 14 disposed in a lower ap-

paratus compartment 15. By heating the generator 14 the refrigerant is expelled from the absorption liquid, condensed in a suitable condenser, and then returned to the evaporator 10 to complete the refrigerating cycle. The 5 weakened absorption liquid from which the refrigerant has been expelled is conducted from the generator 14 to the absorber to absorb refrigerant gas.

The cabinet 12 is provided with a compartment 16 which extends upward from the lower compartment 15 at the rear of the storage compartment 11, and the absorber, condenser, and other parts of the apparatus may be positioned in the lower compartment 15 and the vertically extending compartment 16. In order to simplify the drawings, the last-mentioned parts have not been shown, their illustration not being necessary for an understanding of my invention.

The generator 14 is provided with a heating flue 17 and is adapted to be heated by a gas burner 18 which is arranged so that the flame produced thereby is directed into the lower end of the flue. A suitable combustible gas is delivered from a source of supply through conduit 20, gas filter 21, control mechanism 22, and conduit 23 to the burner 18.

The control mechanism 22, which is interposed between the burner 18 and filter 21 and like that shown in my application referred to above, is provided to control the flow of gas to the burner. Referring to Figs. 4, 8 and 9, the control mechanism comprises a casing 24 having apertured bosses 25 and 26 which form inlet and outlet openings, respectively, for the combustible gas. 30 The gas flows from the inlet opening at the boss 25 through a passage 27 into a diaphragm chamber 28, which is shown most clearly in Fig. 4. From the diaphragm chamber 28 the gas passes into a valve chamber 29 through a passage 30 40 formed in a bushing 31 which is threadedly secured at the open end of the chamber 29. The gas then passes from the valve chamber 29 through a passage 32 to the outlet opening at the boss 26.

Referring to Fig. 4, the right hand side of the bushing 31 forms a valve seat which is adapted to cooperate with a valve 33 having a triangular-shaped stem 34. The stem 34 extends through the passage 30 into the diaphragm chamber 28 50 and is provided at its end with an enlarged head 35. The valve 33 is urged or biased toward its closed or seated position on the bushing 31 by a helical spring 36 disposed within the valve chamber 29. Mechanism, hereinafter to be described, 55

is provided to urge the valve 33 away from the bushing 31 against the tension of the spring 36 to permit gas to flow from the diaphragm chamber 28 through the passage 30 into the valve chamber 29.

The diaphragm chamber 28 is enclosed by a flexible diaphragm 37 having the peripheral edge thereof secured between the open end of the casing 24 and a cover plate 38, a gasket 39 being provided to make the diaphragm chamber 28 gas-tight so that the flow of gas from this chamber to the outlet opening at the boss 26 is insured. To the central portion of the diaphragm 37 is secured a hub member 40 having an opening 41 extending therethrough. To the hub member is secured one face of an expansible diaphragm 42. A yoke member 43 which extends about and beyond the expansible diaphragm 42 is secured to the hub member 40 between the flexible diaphragm 37 and the expansible diaphragm 42. To a pin 44 fixed to a cross piece of the yoke member 43 are pivotally connected the upper ends of levers 45 and 46. A member 47 is pivotally connected at 48 to the lower end of lever 45 and provided with a catch 49 adapted to engage the lower end of the lever 46. A substantially hair-pin-shaped spring 50 is arranged between the levers 45 and 46 whereby the latter are urged apart with the catch 49 adapted to engage the lower end of the lever 46 to prevent the levers from freely moving apart. The lever 45 is positioned adjacent to the expansible diaphragm 42 and provided with a small set screw 51 which is adapted to be contacted by the right hand face of the expansible diaphragm 42.

It will be noted that the expansible diaphragm 42 and opening 41 in the hub member 40 form a completely enclosed space. To the opening 41 of the hub member 40 is secured one end of a capillary tube 52, the opposite end of which is secured to a thermal bulb 53 positioned in thermal contact with the evaporator or cooling element 10, as shown in Fig. 2. The expansible diaphragm 42, capillary tube 52, and thermal bulb 53 constitute what is termed an expansible fluid thermostat which is filled with a suitable fluid which expands with an increase in temperature and becomes reduced in volume with a decrease in temperature.

During normal operation of the refrigerator the levers 45 and 46, which are maintained in fixed position with respect to each other and to the resilient diaphragm 37, cooperate with the expansible diaphragm 42 and the enlarged head 35 of the valve 33 to control the flow of gas to the burner 18. Thus, when the temperature of the evaporator 10 increases, the expansion of the fluid within the diaphragm 42 will cause the latter to expand so as to move the levers 45 and 46 to the right and move the valve 33 away from its seat at the bushing 31. Conversely, when the temperature of the evaporator 10 decreases, the decrease in volume of the fluid within the bellows 42 will cause the latter to contract so as to move the levers 45 and 46 to the left and permit the valve 33 to move toward its seat at the bushing 31. It will now be understood that with the levers 45 and 46 in the position shown in Fig. 4, any movement of the expansible diaphragm 42 is effectively transmitted to the valve 33, the levers in effect acting as a single lever or substantially a rigid motion transmitting linkage. In order that the capillary tube 52 will not appreciably affect any movement of the hub member 40 when the control mechanism is adjusted to its desired position, as

will be hereinafter described, the portion thereof adjacent to the connection at the opening 41 of the hub member 40 is spiral shaped, as shown in Fig. 4.

To adjust the expansible diaphragm 42 at any desired position to fix the position of lever 46 with respect to the head 35 of the valve 33, the cover plate 38 is provided with structure, herein-after to be described, whereby a pulley 54 can be rotated to move a shaft 55 axially toward or away from the hub member 40. The shaft 55 is recessed to receive a pin 56 which is secured to the hub member 40 and provided with a shoulder against which the inner end of the shaft 55 is adapted to bear. It will thus be seen that by rotating the pulley 54 to move the pin 56 axially toward the right, it is operative to move the diaphragm 37 and expansible diaphragm 42 and yoke member 43 carried thereby toward the valve 33 and fix the lever 46 at the desired position with respect to the head 35 of the valve 33. The diaphragm 37 is normally bowed or biased toward the cover plate 38 so that, when the shaft 55 is axially moved toward the left, the flexible diaphragm 37 will of its own accord follow the shaft 55 until it is adjusted to its desired position to fix the lever 46 with respect to the valve 33.

Although the temperature of the cooling element 10 may be controlled at the lower compartment 15 by a dial 57 formed on the cover 30 plate 38 of the control mechanism and by employing a suitable control knob in place of the grooved pulley 54, it is preferred to employ the latter and provide suitable operating mechanism for controlling the refrigerator at the upper compartment 11. As shown in Figs. 1 and 2, an indicating scale or dial 58 is mounted on the front of the cooling element 10 and a cooperating adjustment knob 59 is provided which is fixed to a rod 60 that extends rearwardly through the rear wall 40 of the compartment 11 into the vertical compartment 16. To the rod 60 is secured a grooved pulley 61 which is similar to the grooved pulley 54 and operatively connected therewith by a flexible endless wire 62 having a guide tube 63. It will thus be seen that when the knob 59 at the front of the cooling element is turned, the rod 60 and grooved pulley 61 secured thereto are caused to rotate and effect, through the endless wire 62, rotation of the grooved pulley 54 associated with the control mechanism 22.

The control mechanism 22 is so constructed that only a half turn of the adjustment knob 59 is required to obtain full range adjustment of the thermostat for normal operation of the refrigerator. As shown in Figs. 4 and 5, the inner end of the shaft 55 is provided with a flange having a spiral cam 64 formed thereon which extends about half-way or 180° around the periphery thereof. The cam 64 is adapted to ride on a short radial arm 65 formed at the inner end of the pin 56, the arm 65 being so positioned that the cam 64 is adapted to ride on the arm only when the shaft 55 is moved more than a half turn or 180°. A movement of more than a half turn is imparted to the shaft 55 when the adjustment knob 59 is turned a like amount in a clockwise direction, which, as shown in Fig. 1, will place the knob 59 in the position indicated Defrost on the indicating scale 58. When such a movement of 70 more than a half turn is imparted to the shaft 55, the cam 64 rides on the radial arm 65 and causes the hub member 40 and flexible diaphragm 37 and parts carried thereby to move an abnormal distance toward the valve 33. During this move- 75

ment, the lever 46 contacts the head 35 which is stopped by the bushing 31, whereby the head 35 exerts a force on the lever 46 and causes the latter to move toward the lever 45 against the action of the spring 50 and engage a notch 66 on the member 47. The adjustment knob 59 is then returned to a position at the upper half of the dial 58, and in so turning the knob 59 the cam 64 on the shaft 55 is disengaged from the radial 10 arm 65 formed on the pin 56.

With the lever or part 46 now engaged by the notch 66 of the member 47, the levers 45 and 46 will not be effective to open the valve 33 with a normal increase of the temperature of the cooling element 10 due to the fact that the lever 46 is closer to the lever 45 and spaced from the enlarged head 35 of the valve 33 by the distance between the catch 49 and the notch 66. As the temperature of the cooling element 10 increases, the expandable diaphragm 42 expands and moves the levers 45 and 46 about the pin 44 toward the head 35 of the valve 33. When the cooling element 10 reaches an abnormally high temperature, which temperature is preferably above the freezing temperature of water, the diaphragm 42 expands an abnormal distance toward the valve 33 and moves the lever 45 such a distance that a short arm 67 on the member 47 engages a stop 68 formed on a cross-piece of the yoke member 43. With continued movement of the lever 45 toward the valve 33 due to an abnormal expansion of the diaphragm 42, the member 47 is caused to rotate about the pivot 48 and against the tension of the spring 50 in a clockwise direction, whereby the lower end of the lever 46 is released from the notch 66 and is engaged by the catch 49.

During the period of time the lever 46 is engaged by the notch 66 on the member 47 and does not positively control the valve 33, the valve 33 remains in its closed position providing the temperature of the evaporator 10 is sufficiently low, and the supply of gas to the burner 18 is reduced, as described hereinbefore, thereby decreasing the heating of the generator 14 and permitting the temperature of the cooling element 10 to increase. When the temperature of the cooling element increases to a value above the freezing temperature of water, frost that may have accumulated on the cooling element 10 will melt and can be collected in any suitable manner. The control mechanism is preferably adjusted so that, when the adjustment knob 59 is moved to initiate defrosting of the cooling element 10, the latter will remain at a temperature above the freezing temperature of water sufficiently long to insure substantially complete melting of frost which has accumulated on the cooling element 10.

When the member 47 is caused to move in a clockwise direction so that the lever 46 is released from the notch 66 and engages the catch 49, as described above, the valve 33 is immediately moved to an open position to permit such heating of the generator 14 that the temperature of the cooling element 10 will decrease to a value in the normal operating range of the refrigerator. This normal value of temperature is determined, of course, by the position of the adjustment knob 59 at the upper half of the dial 58 to which it has been returned after being moved momentarily to the lower half of the dial to initiate defrosting.

After the cooling element 10 reaches the normal temperature at which it is adjusted to operate the control mechanism, the levers 45 and 46, which now are in the normal position shown in Fig. 4,

will be operative to control the valve 33 in response to temperature changes of the cooling element 10 to maintain the latter at a substantially constant temperature. When frost has again accumulated on the cooling element 10 to such an extent that defrosting is desired, the adjustment knob 59 is moved to the position of the dial 58 indicated Defrost and then returned to the upper half of the dial to a position at which it is desired that normal operation will resume after the defrosting has automatically terminated.

In starting the refrigerator, the adjustment knob 59 is turned to a definite position at the upper half of the dial 58 and combustible gas, which is adapted to discharge from the end of a tube 69, is ignited to provide a pilot flame for starting the burner 18, as shown in Figs. 1 and 2. Referring to Fig. 6, the tube 69 is connected at 10 to the lower end of a passage 71 formed in the casing 24, the upper end of which passage 20 communicates with a small chamber 72 which in turn is connected by a passage 73 with the diaphragm chamber 28. Within the chamber 72 is disposed a ball valve 74 which is normally maintained in its closed position by a helical spring 75. The front 25 part of the casing 24 is recessed to receive a push button 76 which is provided with a stem 77 adapted to engage the ball valve 74. The push button 76 is normally urged outward by a helical spring 78 whereby the valve 74 remains in its 30 closed position.

When it is desired to provide a pilot flame for starting the burner 18, the push button 76 is pressed inward whereby combustible gas flows 35 from the diaphragm chamber 28 through passage 73, small chamber 72, and passage 71 to the tube 69. A screw 79 extending into the passage 71 is provided to adjust the size of the pilot flame for starting the burner 18. The pilot flame is applied 40 to a heat conductive member 80 which is connected to a safety device 80a, as shown in Fig. 2, the device including a valve connected in conduit 23. After the device 80a becomes sufficiently heated the valve opens whereby gas is delivered to the burner 18 and is immediately ignited by the 45 pilot flame at the end of tube 69. An adjustment screw 81 is provided at the front of the burner 18 to adjust the burner flame and hence the maximum heat input to the generator 14. This adjustment is preferably made when the adjustment 50 knob 59 in the compartment 11 is at a predetermined position, for example, the number three position of the dial 58.

It is also desirable to adjust the minimum heat input to the generator 14 to a value which is 55 small enough to permit defrosting of the evaporator or cooling element 10 and yet adequate to maintain the safety device 80a sufficiently heated to keep the valve associated therewith open and permit gas to be supplied to the burner 18. 60 In order to permit gas to be supplied to the burner when the valve 33 is closed, a by-pass is provided in the casing 24 of the control mechanism 22. As shown in Figs. 7, 8 and 9, gas flows through the by-pass from the diaphragm chamber 28 through passage 81 into passage 82, and from the latter through passage 83 which communicates with the passage 32 at the outlet side of the casing 24. Referring to Fig. 7, the quantity of gas flowing through the by-pass is controlled by a regulating screw 84b having a plug 85a at the inner end thereof which is movable axially in the passage 82 against the tension of a helical spring 86a. By turning the screw 84b after removing the outer screw 84a, the plug 85a

can be positioned in the passage 82 to control the quantity of gas which can flow from the passage 81 into the passage 82 and thence through passage 83 to the burner 18.

- 5 In order to make the minimum flame adjustment for the burner 18, it is necessary to close the main valve 33. In many instances, particularly when a refrigerator is being installed, the evaporator 10 is above a predetermined low temperature and it would require operating the refrigerator for a relatively long period of time in order to effect closing of the main valve 33 with the parts of the control mechanism 22 thus far described.
- 15 In accordance with my invention, the control mechanism 22 is so constructed and arranged that the main valve 33 can be closed at any time to adjust or check the minimum heat input to the generator 14. Referring to Figs. 4 and 5, the 20 mechanism for closing the main valve 33 to check or adjust the quantity of gas flowing through the by-pass to provide the minimum heat input to the generator 14 is included in the structure provided on the cover plate 38. As shown, the shaft 25 55, which is provided with a recess to receive the pin 56, extends through a sleeve 84 of shorter length. The inner end of sleeve 84 is adapted to bear against the flange on the shaft 55 on which the cam 64 is formed, and the outer end 30 thereof is provided with a multi-sided enlarged head 85. The outer end of the shaft 55 is cut away, as indicated at 86, and the extreme threaded end is adapted to receive a clamping nut 87 for drawing the inner flanged end of the shaft 35 55 against the inner end of the sleeve 84 and also secure a cap 88 over the outer end of the shaft 55 and multi-sided head 85 of the sleeve 84. The grooved pulley 54 is positioned over the cap 88 and secured thereto, as by a set screw 40 89. By rotating the grooved pulley 54, therefore, the shaft 55, sleeve 84, cap 88, and grooved pulley 54 are turned as a unit.

The sleeve 84, which may be termed an inner sleeve, is externally threaded and adapted to move axially within an internally threaded shorter outer sleeve 90. The outer sleeve 90 is also externally threaded and adapted to move axially within a threaded central opening formed in the cover plate 38. As shown in Figs. 3 and 5, the outer sleeve 90 is provided with an arm 91 45 having a recess at the outer end thereof adapted to receive a set screw 92 secured to the front of the cover plate 38. The arm 91 is also provided with a raised portion 93 which is in the 50 path of movement of an inwardly extending projection 94 formed on the cap 88.

The external threads of the inner sleeve 84 and internal threads of the outer sleeve 90 are left-hand threads whereby, when the grooved pulley 54 is turned in a counter-clockwise direction, the shaft 55 is moved axially toward the valve 33; and conversely, when the grooved pulley is turned in a clockwise direction, the shaft 55 is moved axially away from the valve 33. The 60 left-hand threads per inch provided on the inner and outer sleeves 84 and 90 are such that, for a half turn of the adjustment knob 59 and a half turn of the grooved pulley 54, full range adjustment of the thermostat is obtained for normal 65 operation of the refrigerator. In other words, for a half turn of the grooved pulley 54 the cam 64 at the inner end of the shaft 55 is not in operation and the expansible diaphragm 42 and levers 45 and 46 are moved toward and away 70 from the valve 33 a distance corresponding to the 75

axial movement of the shaft 55 and inner sleeve 84. This normal range of operation is indicated by the numerals 1 to 5 on the indicating scale 57 on the cover plate 38 and indicating scale 58 in the upper compartment 11 of the cabinet 12. For this particular half turn, the levers 45 and 46 are in the position shown in Fig. 4 and cooperate with the expansible diaphragm 42 and enlarged head 35 of the valve 33 to control the flow of gas to the burner 18 in response to the temperature of the cooling element 10, as described above. And the temperature at which the cooling element is maintained is determined by the position of the expansible diaphragm 42 and levers 45 and 46 with respect to the valve 33, which temperature is indicated by the position of the adjustment knob 59 in the upper compartment 11. By providing the raised portion 93 on the arm 91, the inwardly extending projection 94 on the cap 88 will limit the extent of counter-clockwise movement of the adjustment knob 59 so that the highest end of the cam 64 will not strike the radial arm 65 and thus injure parts of the control mechanism 22 within the casing 24.

When the adjustment knob 59 is turned in a clockwise direction past the numeral 5 on the indicating scale 58, axial movement is imparted to the shaft 55 in a direction away from the valve 33. This places the adjusting knob 59 in the lower part of the indicating scale marked Defrost. Although the shaft 55 is moved axially away from the valve 33 with such clockwise movement of the adjustment knob 59, the cam 64 now becomes effective and rides over the radial arm 65 and forces the hub member 40 and flexible diaphragm 37 and parts carried thereby an abnormal distance toward the valve 33. This abnormal movement of the diaphragm 37 toward the valve 33 is obtained by making the pitch of the cam 64 relatively high so that movement of the resilient diaphragm 37 toward the valve is effected even though the shaft 55 is being moved away from the valve 33. After the levers 45 and 46 have been moved closer together due to such abnormal movement of the diaphragm 37, as described above, the adjustment knob 59 is returned to the desired position at the upper half of the indicating scale 58 which will determine the low temperature at which the cooling element 10 will be maintained after defrosting has automatically terminated. With such return movement of the adjustment knob 59, cam 64 no longer cooperates with the radial arm 65 and the flat portion of the flange on which the cam is formed bears against the hub member 40. One complete turn of the adjustment knob may be considered effective to impart an axial movement to the expansible diaphragm 42 and levers 45 and 46 in a normal operating range to determine the temperature at which it is desired to maintain the evaporator 10 and to move the lever 46 from its normal position at catch 49 to its second position at notch 66.

The outer sleeve 90 is normally so positioned within the opening in the cover plate 38 that the arm 91 bears lightly against the front cover plate 38 and is locked in position by the set screw 92, as shown most clearly in Fig. 3. The inner sleeve 84 is so positioned axially with respect to the outer sleeve 90 that normal control of the refrigerator, as well as defrosting thereof, will be effective in the manner just described. The external threads formed on the outer sleeve 90 and at the opening of the cover plate 38 are right-hand threads.

In order to close the valve 33 to adjust or regulate the quantity of gas flowing through the by-pass passages 81, 82, and 83, the set screw 92 on the cover plate 38 is loosened and the arm 91 is turned counter-clockwise one complete revolution until the arm strikes the set screw 92. With such movement of the arm 91 an axial movement is imparted to the outer sleeve 90 in a direction away from the valve 33, and, due to the frictional engagement between the outer sleeve 90 and inner sleeve 84, the entire structure provided on the cover plate 38 is moved in a direction away from the valve 33 along with the outer sleeve 90. The number of right-hand threads per inch formed 10 on the sleeve 90 and opening in the cover plate 38 are less than the number of left-hand threads per inch on the outer sleeve 90 and inner sleeve 84, so that the axial movement effected by the outer sleeve 90 is greater than that effected by 20 the inner sleeve 84 for a given rotation of the sleeves. The number of threads per inch formed on the sleeve 90 and opening is preferably such that, with one complete revolution of the arm 91, the shaft 55 moves axially away from the valve 33 a sufficient distance to cause the resilient diaphragm 37 to bow toward the cover plate 38 and 25 permit the valve 33 to close. The axial movement imparted to the outer sleeve 90, therefore, permits the expansible diaphragm 42 to move beyond the normal operating range in which movement thereof is effected by the adjustment 30 knob 59.

With the valve 33 in its closed position, the flow of gas through the by-pass passages can be adjusted, as described above, and the arm 91 then rotated in a clockwise direction to its normal position at the set screw 92. With the arm 91 locked in position by the set screw 92, the shaft 55 is again in its normal position whereby the refrigerator can be controlled by means of the adjustment knob 59 in the upper compartment 11.

In view of the foregoing, it will be understood that I have provided a control mechanism which effectively controls the flow of gas to the burner in response to a temperature condition affected by the cooling element, permits at will the instigation of defrosting which terminates automatically, and also enables the main valve to be closed at any time so that the minimum heat input to the generator can be adjusted by regulating the flow of gas through the by-pass passage provided around the main valve. By providing the shaft 55 with a recess to receive the pin 56 secured to the hub member 40, the resilient diaphragm 37 is always guided with any axial movement of the shaft 55, so that any cocking of the diaphragm tending to injure the latter is avoided.

Although I have shown my improved control mechanism in connection with a particular type of refrigerator, I do not wish to be limited to the particular arrangement set forth, and I intend in the following claims to cover all modifications which do not depart from the spirit and scope of my invention.

65 What is claimed is:

1. In an absorption type refrigerator including a cooling element and a generator adapted to be heated by a fluid fuel burner, a main valve for controlling flow of fuel to said burner, a by-pass 70 for fuel around said main valve, an adjustable valve in said by-pass, structure comprising a single thermostat normally operative to regulate said main valve to maintain said cooling element at a substantially constant temperature, said structure being capable of modifying the normal

regulation of said main valve so that the latter is open only upon an abnormally high increase in temperature and operative to resume said normal regulation responsive to the abnormally high temperature, means operative to adjust said 5 structure to determine the substantially constant temperature at which it is desired to maintain said cooling element and to cause said structure to modify said normal regulation of said main valve, and additional means operative to 10 adjust said structure irrespective of the temperature of said cooling element for closing said main valve so that adjustment of said by-pass valve can be effected at will to regulate the size of the minimum flame produced by said burner. 15

2. In an absorption type refrigerator including a cooling element and a generator adapted to be heated by a fluid fuel burner, a valve for controlling flow of fuel to said burner, structure comprising a single thermostat normally operative 20 to regulate said valve to maintain said cooling element at a substantially constant temperature, said structure being capable of modifying the normal regulation of said valve to reduce the flow of fluid fuel to said burner and operative to 25 resume said normal regulation responsive to an abnormally high increase in temperature, means operative to adjust said structure in a normal operating range to determine the substantially constant temperature at which it is desired to 30 maintain said cooling element, said structure being so constructed and arranged that said valve is open when said cooling element is above a pre-determined temperature and while said structure is in said normal operating range, and additional 35 means operative to adjust said structure beyond said normal operating range for closing said valve while said cooling element is above the pre-determined temperature.

3. In an absorption type refrigerator including a cooling element and a generator adapted to be heated by a fluid fuel burner, a main valve for controlling flow of fuel to said burner, a by-pass for fuel around said main valve, an adjustable valve in said by-pass, a thermostat element 40 normally operative responsive to a temperature condition affected by said cooling element, structure operatively associating said thermostat element and said main valve so that the flow of fuel is increased and decreased upon increase and 45 decrease respectively of temperature, said structure being adjustable to modify said operative relation of said thermostat element and said main valve so that the flow of fuel is increased only upon an abnormal rise of temperature and 50 operative to terminate said modified operative relation upon said abnormal rise of temperature, means operative to adjust said structure in a normal operating range with respect to said main valve to determine the normally produced condition of temperature and to cause said structure to modify said operative relation of said thermostat element and said main valve, and additional 55 means operative to adjust said structure beyond said normal operating range for closing said main valve irrespective of said temperature condition, so that adjustment of said by-pass valve can be effected at will to regulate the size of the minimum flame produced by said burner. 60

4. In an absorption type refrigerator including 70 a cooling element and a generator adapted to be heated by a fluid fuel burner, a main valve for controlling the flow of fuel to said burner, a by-pass for fluid fuel around said main valve, an adjustable valve in said by-pass, structure 75

normally responsive to a temperature condition affected by said cooling element for controlling said main valve to maintain a normally produced condition of temperature, said controlling means including a part in its normal position, said part being movable from its normal position to a second position to modify the control of said main valve to permit said cooling element to increase to an abnormally high temperature, said structure being operative when said cooling element increases to the abnormally high temperature to move said part back to its normal position so that said structure is operative to resume maintaining a normally produced condition of temperature, means operative to adjust said structure in a normal operating range to determine the normally produced condition of temperature and to cause said part to move from its normal position to the second position, said structure being so constructed and arranged that in the normal operating range said main valve is normally open when the condition of temperature is above a predetermined value, and additional means operative to adjust said structure beyond the normal operating range for closing said main valve when the condition of temperature is above the predetermined value, so that adjustment of said by-pass valve can be effected to regulate the size of the minimum flame produced by said burner.

5. In an absorption type refrigerator including a cooling element and a generator adapted to be heated by a fluid fuel burner, a main valve for controlling the flow of fuel to said burner, a by-pass for fuel around said main valve, an adjustable valve in said by-pass, structure normally responsive to a temperature condition affected by said cooling element for controlling said main valve to maintain a normally produced condition of temperature, said structure being capable of modifying the normal regulation of said main valve so that the latter is open only upon an abnormal increase in temperature and operative to resume said normal regulation responsive to said abnormally high temperature, a part having an opening, and means including an outer sleeve member in threaded engagement with the opening and an inner sleeve member in threaded engagement with said outer member for adjusting said structure, the axial movement effected by said outer member being greater than that effected by said inner member for a given rotation of said members, rotation of said inner member being operative to adjust said structure in a normal operating range to determine the normally produced condition of temperature and to cause said structure to modify said normal regulation, said structure being so constructed and arranged that said main valve is open when said cooling element is above a predetermined temperature and while said structure is in the normal operating range, rotation of said outer member being operative to adjust said structure beyond the normal operating range for closing said main valve while said cooling element is above the predetermined temperature, so that adjustment of said by-pass valve can be effected to regulate the size of the minimum flame produced by said burner.

6. In an absorption type refrigerator including a cooling element and a generator adapted to be heated by a fluid fuel burner, a main valve having a stem for regulating the flow of gas to said burner, a by-pass for fluid fuel around said main valve, an adjustable valve in said by-pass, means

for biasing said main valve to its closed position, structure including an expansible fluid thermostat element for normally controlling said main valve to maintain said cooling element at a substantially constant temperature, said structure including a part in its normal position and operatively associated with said stem, said part being movable toward said stem and said biasing means to cause said stem to contact and force said part to assume a second position and also movable away from said stem to a position in a normal operating range, the movement of said part from its normal position being effective to alter the normal control of said main valve so that said cooling element will increase to an abnormally high temperature, the expansion of fluid within said fluid thermostat element being effective when said cooling element reaches the abnormally high temperature to move said part back to its normal position so that the latter is operatively associated with said stem to control said main valve, means operative to adjust said structure in the normal operating range to determine the substantially constant temperature at which it is desired to maintain said cooling element and to cause said part to assume the second position to alter the normal control of said main valve, said structure being so constructed and arranged that said main valve is open when said cooling element is above a predetermined temperature and while said structure is in the normal operating range, and additional means operative to adjust said structure away from said main valve and beyond the normal operating range to permit said biasing means to close said main valve while said cooling element is above a predetermined temperature, so that adjustment of said by-pass valve can be effected to regulate the size of the minimum flame produced by said burner.

7. In a refrigerator including a system having an evaporator for cooling and a heated generator and having a heater for heating the generator and a control device for regulating flow of fuel to the heater, said control device including main flow and by-pass structure, an actuating device including an expansible and contractible body, means for expanding and contracting said body for regulating flow of fuel, primary adjusting means for bodily moving said body, means limiting movement of said primary adjusting means to a relatively small range, and mechanism for bodily moving said body beyond the range possible with the primary adjusting means to limit flow of fuel to by-pass flow when said body is abnormally expanded, and means to adjust by-pass flow.

8. In a refrigerator including a system having an evaporator for cooling and a heated generator and having a heater for heating the generator and a control device for regulating flow of fuel to the heater, said control device including main flow and by-pass structure, an actuating device including an expansible and contractible body, primary adjusting rotary means for bodily moving said body, means limiting movement of said primary adjusting rotary means to less than 360°, and mechanism including rotary means for bodily moving said body beyond the range possible with the primary adjusting rotary means to limit flow of fuel to by-pass flow when said body is abnormally expanded, and means to adjust by-pass flow.

9. In a refrigerator including a system having an evaporator for cooling and a generator, a heater for heating the generator, and a control

device for controlling rate of energy supply to the heater, the control device including structure to supply energy to the heater at a main rate and at a reduced rate, means including a thermostat element for operating the control device to control the main rate of energy supply, primary adjusting means for adjusting the thermostat element, means limiting movement of said primary adjusting means to a relatively small range,

and mechanism for adjusting the thermostat element beyond the range possible with said primary adjusting means to limit the energy supply to the reduced rate when the thermostat element is subject to a temperature above a predetermined value, and means to adjust the reduced rate of energy supply. 5
